COMBINED MEAT AND CHEESE RACK AND CUTTING BLOCK

Robert L. Stuart, R.R. 3, Syracuse, Ind. 46567

Filed Aug. 8, 1969, Ser. No. 18,585

Term of patent 7 years

Int. Cl. D15—99; D6—01

U.S. Cl. D11—1

FIG. 1

FIG. 2

FIG. 3

FIG. 4

FIG. 5

FIG. 6

FIG. 7

FIG. 1 is a perspective view of a combined meat and cheese rack and cutting block embodying the present design;

FIG. 2 is a front elevational view;

FIG. 3 is an elevation of the end of the cutting block opposite the end shown in FIG. 1;

FIG. 4 is a top plan view;

FIG. 5 is a rear elevational view;

FIG. 6 is an enlarged, fragmentary cross-sectional view taken on line 6-6 of FIG. 4; and

FIG. 7 is an enlarged, fragmentary cross-sectional view taken on line 7-7 of FIG. 4.

I claim:

The ornamental design for a combined meat and cheese rack and cutting block, substantially as shown.
